UNITED STATES PATENT OFFICE.

MATTHEW DANIEL TOOHEY, OF GALVESTON, TEXAS.

PUSH-BAR FOR LOCOMOTIVES.

SPECIFICATION forming part of Letters Patent No. 400,518, dated April 2, 1889.

Application filed December 21, 1888. Serial No. 294,321. (No model.)

To all whom it may concern:

Be it known that I, MATTHEW DANIEL TOOHEY, a citizen of the United States, residing at Galveston, in the county of Galveston 5 and State of Texas, have invented new and useful Improvements in Push-Bars for Locomotives, of which the following is a specification.

My invention relates to improvements in 10 push-bars for locomotives; and it consists in certain novel features hereinafter described and claimed.

In the accompanying drawings, Figure 1 is 15 a perspective view showing the cow-catcher and my push-bar in position for coupling to a car. Fig. 2 is a front elevation showing the push-bar swung around to the side, as it appears when not in use. Fig. 3 is a horizontal section of the push-bar.

20 Referring to the drawings by letter, A designates the cow-catcher, of the usual or any preferred construction, and provided with the cross bar or sill B at its upper rear edge, as shown. To the cross bar or sill B, at the ends 25 of the same, I secure the castings C, which are provided with the forwardly-projecting perforated lugs D, between which the end of the push-bar is adapted to fit when not in use, as will be presently more fully described.

30 At the center of the cross bar or sill B, I secure the support E, having the forwardly-projecting perforated lugs or ears F, as shown.

The push-bar comprises the draw-head G and the coupling-bar H. The rear end of the 35 draw-head is inserted between the ears F and pivoted between the same by a pin, I, inserted vertically downward therethrough, and having a spring, J, formed integrally with its upper end and projecting forward therefrom.

40 A supporting-pin, K, is secured to the free end of this spring and projects downward through the draw-head, and is provided at its lower end with an annular shoulder or head, L, which bears against the under side of the 45 draw-head, and thereby supports the push-bar in proper position for coupling. By providing this spring and supporting-pin I am enabled to make the joint between the draw-head and the support E sufficiently loose to 50 allow the proper play of the draw-head and yet prevent the draw-head having such vertical movement as will prevent the proper

coupling of the same to the car. The forward portion of the draw-head is hollow, and it is provided in its sides with the longitudinal 55 slots M, which communicate with the hollow interior of the draw-head. The front end of the draw-head is made somewhat wider than the rear portion of the same, thereby providing the vertical shoulders N. The 60 coupling-bar H has its rear end fitting in the hollow interior of the draw-head, and is provided on its sides with the wings O, which rest against the outer sides of the draw-head, and have their front edges adapted to contact 65 with the vertical shoulders N of the draw-head and thereby limit the forward motion of the coupling-bar. The said wings are connected to the coupling-bar by means of the lateral extensions P, which slide in the slots 70 M in the sides of the draw-head, as shown. The coupling-bar is further provided at its opposite ends with the openings Q R, the opening Q being adapted to receive the coupling-pin carried by the draw-head of the coupling 75 on the car, while the opening R is adapted to receive a locking-pin to lock the coupling-bar in its extended position. The said locking-pin is mounted in a cylinder or sleeve, S, erected on the upper side of the draw-head at 80 the front end of the same, and has its lower end normally resting on the coupling-bar and supported thereby, so that when the coupling-bar is drawn forward and the opening R is brought under the said pin the pin will automatically fall into engagement with the said opening and lock the coupling-bar in its extended position.

In practice, when it is desired to couple the locomotive to a car, the coupling-bar is drawn 90 forward to the front end of the draw-head, as shown in Fig. 1, and the front end of the coupling-bar is then coupled to the car in the usual manner, as will be readily understood. When the push-bar is not in use, the locking-pin is raised and the coupling-bar pushed 95 backward, after which the push-bar is swung around to the side, as shown in Fig. 2, and locked in the said position by inserting a suitable pin through the perforations in the lugs D and the opening Q in the end of the coupling-bar.

My improved device is very simple in its arrangement and is composed of few parts,

so that it can be manufactured at a small cost and is not liable to get out of order. When the device is not in use and it is moved around to the side, as shown and described, 5 it is out of the way and occupies but very little room.

Having thus described my invention, what I claim, and desire to secure by Letters Patent, is—

- 10 1. A push-bar for locomotives, comprising a horizontally-swinging draw-head and a coupling-bar carried by said draw-head and adapted to slide longitudinally therein, as set forth.
- 15 2. A push-bar for locomotives, comprising a draw-head having a vertical sleeve or cylinder on its upper side, a coupling-bar sliding in the draw-head and having an opening in its inner end, and a locking-pin mounted 20 in the sleeve or cylinder and adapted to engage the opening in the coupling-bar, as set forth.
- 25 3. The combination, with the support E, of the draw-head pivoted thereto, the coupling-bar carried by the draw-head, the spring projecting from the upper end of the pivot-pin of the draw-head, and the supporting-pin secured to said spring and extending downward through the draw-head, and provided at its 30 lower end with an annular shoulder bearing against the under side of the draw-head, as set forth.
- 35 4. The combination of the draw-head, having slots in its sides and provided with the vertical shoulders N, and the coupling-bar sliding in the draw-head and having lateral extensions projecting through the slots in the draw-head, and provided with the wings

O, bearing against the sides of the draw-head and adapted to contact with the shoulders N, 40 as set forth.

5. A push-bar for locomotives, comprising a horizontally-swinging draw-head pivoted to the front end of the locomotive, and carrying a coupling-bar which is adapted to slide longitudinally within the draw-head. 45

6. The improved push-bar for locomotives herein described and shown, comprising the support E, the horizontally-swinging draw-head, the coupling-bar carried by the draw-head and adapted to slide longitudinally therein, the casting adapted to receive the end of the coupling-bar when not in use, the pin pivoting the end of the draw-head to the support E, the spring projecting from the upper end of said pivot-pin, and the supporting-pin depending from said spring and supporting the draw-head, as specified. 50

7. A push-bar for locomotives, comprising a horizontally-swinging draw-head carrying a coupling-bar, and the pin for locking the draw-head to hold it from swinging, as set forth. 60

8. A push-bar for locomotives, comprising a horizontally-swinging draw-head carrying a coupling-bar, and the pin for locking the draw-head to hold it from swinging, and the eastings C on either side to lock the draw-head when swung around, as set forth. 65

In testimony that I claim the foregoing as my own I have hereto affixed my signature in 70 presence of two witnesses.

MATTHEW DANIEL TOOHEY.
